UNITED STATES PATENT OFFICE.

JAMES I. AYER, OF MALDEN, MASSACHUSETTS, ASSIGNOR TO SIMPLEX ELECTRIC HEATING COMPANY, OF BOSTON, MASSACHUSETTS, A CORPORATION OF MASSACHUSETTS.

ELECTRIC SOLDERING-IRON.

SPECIFICATION forming part of Letters Patent No. 731,838, dated June 23, 1903.

Application filed March 5, 1902. Serial No. 96,795. (No model.)

To all whom it may concern:

Be it known that I, JAMES I. AYER, a citizen of the United States, residing at Malden, county of Middlesex, State of Massachusetts, have invented an Improvement in Electric Soldering-Irons, of which the following description, in connection with the accompanying drawings, is a specification, like letters on the drawings representing like parts.

10 My invention is an electric soldering-iron, the principal objects thereof being the provision of increased heat effectiveness and the provision of increased life or durability.

Soldering-irons must be comparatively 15 small and are required to be of prescribed general shape, as well as size, and it is also desirable that they should have minimum weight and that the heat should not be wasted and should be confined to the active 20 end or operative region of the iron, and accordingly it is the purpose of my invention to attain these ends.

In carrying out my invention I provide a 25 heat-convector of special construction which coöperates with a soldering-tip at one end and with a heat-generator toward its other end and is surrounded by heat equalizing and retaining means, including a special casting or shell.

30 The constructional details and other advantages of my invention will be more fully pointed out in the course of the following description, reference being had to the accompanying drawings, in which I have illustrated 35 a preferred embodiment of my invention.

In the drawings, Figure 1 is a perspective view of a detail constructed according to my invention. Fig. 2 is a longitudinal sectional view thereof. Fig. 3 shows the core and adjacent parts in side elevation. Fig. 4 is an 40 end elevation thereof.

It will be understood that the handle end 45 *a* of the tool may be of any usual or desired construction, and accordingly I have not shown and will not describe details thereof.

My invention relates more directly to the core and the adjacent and connected parts.

The core is composed of highly-conductive material and comparatively large size, being

preferably made of copper, and comprises a 50 reduced part *b*, provided at one end with a heavy peripheral shoulder *b'* and a threaded boss *b''* for receiving a soldering-tip *c* of usual or any preferred size and shape. The shoulder and the body of the core being in one 55 piece and arranged to receive the tip in direct engagement therewith throughout as large a contacting area as possible, gives free direct transmission of heat from the core to the tip.

It is necessary in a soldering-iron that the 60 tip should be capable of extended use, and hence it must have considerable mass, and yet as, in spite of this fact, it will quickly wear out I make it removable, so as to reduce to a minimum the cost of use of the 65 electric soldering-iron, the removability permitting all the expensive portion of the tool to remain permanently with the handle.

The construction of core gives a large contact-surface where the tip is joined and also 70 gives a large capacity for the transmission of heat by conduction, which, as is well known, is far more rapid than any other means of transmission and gives a continuous metallic conductor of large conducting 75 capacity which tends to concentrate all the heat of the electric heat-generator at and toward the soldering-point *c*.

The heat-generator may be of any construction adapted to the purpose, and for convenience I have shown the conventional coil of fine wire, which receives its current from circuit-wires *d d'*.

All the constructional details of my invention conspire to securing the greatest amount 85 of heat with the least possible number of turns of the resistance-wire, from one to three layers *d''* of the coil being entirely sufficient for the ordinary iron with a comparatively short core, these layers being herein shown 90 as separated from each other by mica insulators *d''*.

As already intimated, a tool of this kind must be limited in size and weight, and yet there must be a concentration of ample heat 95 at the tip end, and while increasing the diameter of the core enables me to provide a heat-generator of thin cross-section sufficient to

- produce the requisite heat by bringing the generator into closer contact with the conducting material of the core and the large mass of the latter also affords a free path by conduction for the heat to the tip I accomplish this without increasing the weight, and at the same time I provide means for directing the heat toward the tip end and preventing the same from passing as freely in the opposite direction by making the upper or right-hand end of the core more or less hollow, as indicated at b^3 , where I have shown a conical recess. This avoids increasing the weight while providing relatively large mass of conducting material, as already explained, the core being relatively thin at its upper end, where it receives the heat of the first few turns of resistance-coil, and grows gradually thicker or greater in mass as it approaches the soldering-point end and is called upon to receive and conduct away the increasing or accumulating supply of heat, which becomes greater and greater as that end of the core is approached.
- 25 Coöperating with the foregoing in conserving the heat for practical use I provide an air-chamber e around the core, this air-chamber being inclosed by a casing f , which constitutes the upper portion of the external part of the soldering-iron, and by a diaphragm or head g , of poor or non conducting material, preferably in the form of a mica washer, which extends transversely of the jacket f , into peripheral contact therewith, and is secured against the end of the core by any suitable means, as by a clamping-ring g' and setscrew g^2 . This construction I regard as of much value. I have also shown the parts held in place by dowels g^3 and the screw g^3 as screwing into a plug g^4 . The closed air-chamber tends to prevent the loss of heat by convection-currents or air circulation, which would occur if it were not a closed chamber, and the thin casing f , which is secured to the shoulder b' at f' and carries the handle at f'' , gives a minimum tendency to conduct heat longitudinally away from the superior conductor provided in the large mass of conductive material at the soldering end of the tool.
- 50 Preferably the casing or shell f is secured to the core in such a manner as to prevent a ready conduction of heat from the core to the casing and prevent access of soldering-acids to the electric heat-generator, the construction herein shown comprising a groove lined with asbestos or mica or filled with non-conducting cement or other material f^5 calculated to withstand the high temperature and the action of strong acid without being easily destroyed. This performs the threefold office of preventing contact of the shell with the metal of the core, securing the shell and the connected handle, &c., rigidly in place, and preventing the entrance of acid used in soldering.
- 55 The shell is composed of material, preferably thin metal, having slow conductive or

heat-transmitting capacity in the direction of its length, but good heat-transmitting capacity transversely of its length. This construction prevents automatically the tool from destroying itself by an undue increase in temperature while idle.

As is well known, the work required of a soldering-iron is quite intermittent, and yet the current is usually kept the same under all conditions, so that there must be a sufficient current to render the soldering-iron effective while being used, and therefore when not in use if the heat were confined absolutely the temperature would rise excessively, and it becomes desirable, therefore, to provide an inclosing medium which will freely permit the radiation—*i.e.*, transverse passage of heat—from the core whenever the heat thus rises.

When the iron is in use, the energy is utilized in work; but during the longer or shorter periods of time when the current-supply is continued but the iron is idle all of the heat generated must be disposed of entirely by radiation from the exposed surfaces. The loss of heat under the latter conditions is usually much less rapid than under conditions of work, and accordingly I provide the special construction of shell which facilitates radiation or transverse disposal of the heat and permits the degree of radiation to increase with the rise in temperature. The radiation losses except at high temperatures are not material—as, for instance, at 400° or 500° Fahrenheit radiant heat does not penetrate a great distance—and hence the air-jacket conserves the heat at the lower temperatures and prevents loss, except to a very feeble amount; but as the temperature increases the radiant heat becomes such that it readily penetrates the thin conductive casing and escapes freely to the outside atmosphere. In other words, this feature of my invention provides a shell which permits free radiation of heat at high temperatures when the iron is doing no work; but when the iron is at work and heat would naturally be lost by longitudinal conduction from the shoulder b' along the shell or casing the insulated and non-conductive character of the construction prevents such loss. In a manner this thin shell is automatic because as the temperature rises it relieves the iron with sufficient rapidity to keep down very materially the temperature, while at working temperatures the losses therefrom are comparatively slight. The core and its shoulder being one piece and the joint with the shell being non-conducting and the joint with the tip being such as to permit the best and freest conduction coöperate with the other features already explained in bringing the greatest efficiency of heat effects at the tip of the tool.

The construction above explained makes it entirely feasible to operate the heater with a comparatively low temperature in the resistance-wires because of the few turns of wire,

one over the other, resulting in close proximity of all wires to the core, and also because the core is of comparatively large mass and high conductivity, which rapidly conducts heat therefrom to the tip *c*. These two features I regard as of great importance in my invention—namely, the construction which permits the heat-generator to operate at a low temperature, whereby the life of the heater is increased, and the provision of means for freely taking the heat away from the wire by the core and easily conducting it to the work, whereby the losses of heat are reduced to a minimum and the efficiency of the tool is increased.

Without entering more fully upon the advantages of my invention I wish it understood that I do not limit myself to the constructional details herein explained other-
wise than as expressed in the claims, inasmuch as many changes and modifications may be resorted to without departing from the spirit and scope of my invention.

Having described my invention, what I claim as new, and desire to secure by Letters Patent of the United States, is—

1. A soldering-iron, comprising an electric heat-generating coil of substantially uniform thickness, or number of turns, from end to end, a core therefor of substantially uniform external diameter from end to end, and soldering-tip, said core being provided with increased mass toward the end carrying said soldering-tip by means of a tapering cavity 35 with the apex pointing toward said soldering-tip end.

2. A soldering-iron, comprising an electric heat-generator, a core therefor and soldering-tip, said soldering-tip being carried at one end of said core, the core, excepting adjacent said tip, and the heat-generator being surrounded by an air-chamber, and a mica barrier supporting said casing out of contact with the heat-generator.

45 3. A soldering-iron, comprising an electric heat-generator, a core therefor and soldering-tip, a casing surrounding and insulated from said core having large capacity for trans-

verse heat transmission and small capacity for longitudinal conduction, and a diaphragm 50 or barrier *g* of poor conducting material extending in peripheral contact with said jacket or casing and forming with the latter a dead-air chamber about said coil and core.

4. A soldering-iron, comprising a core of 55 high conductive material having a reduced upper portion and a radial shoulder adjacent its effective end, a soldering-tip therefor, an electric heat-generator mounted on said reduced portion, a thin casing secured to said 60 shoulder and inclosing said resistance-coil, having a free air-space between the latter and said casing, and a washer or diaphragm of poor conducting material carried at the upper end of said core and extending radially into 65 peripheral contact with said casing.

5. A soldering-iron, comprising an electric heat-generator, a soldering-tip, means for conveying the heat from said generator to said tip, and a casing electrically insulated from said 70 heat-generator and tip and inclosing said heat-generator, said casing having large capacity for transverse heat transmission and small capacity for longitudinal conduction, and having a free air-space separating the same from 75 said heat-generator.

6. A soldering-iron, comprising an electric heat-generator, a soldering - tip, means for conveying the heat from said generator to said tip, and a casing electrically insulated 80 from the heat-generator and inclosing said electric heat-generator, out of contact therewith, and secured in place by a heat-insulation joint.

7. In a soldering-iron, an electric heat-generator, heat-conveying means, a casing, and means, including a groove in said heat-conveying means lined with non-heat-conducting material, for retaining said casing.

In testimony whereof I have signed my 90 name to this specification in the presence of two subscribing witnesses.

JAS. I. AYER.
